UNITED STATES PATENT OFFICE.

TAKUMA KAJIWARA, OF ST. LOUIS, MISSOURI.

DESIGN FOR A MOUNT FOR PHOTOGRAPHS.

46,950.

Specification for Design.

Patented Feb. 16, 1915.

Application filed November 7, 1914. Serial No. 870,925. Term of patent 7 years.

To all whom it may concern:

Be it known that I, TAKUMA KAJIWARA, a subject of the Emperor of Japan, residing at the city of St. Louis, State of Missouri, have invented a new, original, and ornamental Design for Mounts for Photographs, of which the following is a specification, reference being had to the accompanying drawings, forming part thereof.

Figure 1 is a front elevational view of a mount for photographs showing my new design. Fig. 2 is a side elevational view of a mount for photographs embodying my new design.

I claim:

The ornamental design for a mount for photographs, as shown.

TAKUMA KAJIWARA.

Witnesses:

M. P. SMITH,
M. A. HANDEL.
